Primary Examiner — Elizabeth J Oswecki*(74) Attorney, Agent, or Firm* — Oblon, McClelland,
Maier & Neustadt, L.L.P.(57) **CLAIM**

The ornamental design for a heater, as shown and described.

DESCRIPTION

FIG. 1 is a top plan view of a heater showing our new design;

FIG. 2 is a bottom plan view thereof;

FIG. 3 is a front elevation view thereof;

FIG. 4 is a back elevation view thereof;

FIG. 5 is a left side elevation view thereof; and,

FIG. 6 is a right side elevation view thereof.

The broken lines in the drawings illustrate subject matter that forms no part of the claimed design.

1 Claim, 5 Drawing Sheets(56)
